TRANSMITTER FOR STEP-BY-STEP
TELEGRAPH SYSTEMS

Alfred Edward Thompson and Reginald Dennis Salmon, Croydon, England, assignors to Creed and Company Limited, Croydon, Surrey, England

Application December 29, 1937, Serial No. 182,201
In Great Britain January 12, 1937

9 Claims. (Cl. 178—79)

This invention relates to transmitters for step-by-step type printing telegraph apparatus, and has for its object to provide such a transmitter that will be cheap to construct, that requires for signalling purposes two line conditions only, and that can be operated by an unskilled person.

According to one feature of this invention we provide a step-by-step transmitter in which transmitting contacts are operated by means of a shaft that sends only two or four impulses per revolution of the shaft.

This enables a keyboard to be used for controlling the transmission of the signals, having the keys arranged in a plurality of rows as in a teleprinter or typewriter. Other features of the invention comprise arrangements for locking a depressed key in depressed position and preventing any other key being depressed until the required number of impulses have been sent; and for preventing the simultaneous depression of two keys. An important feature of the invention is that a delay period occurs between the depression of a key and the commencement of the transmission of impulses since this delay ensures a definite pause between successive series of impulses.

The nature of the invention will be better understood from the following description of one embodiment of the invention taken in conjunction with the accompanying drawings, in which:

Fig. 1 is a plan view of the apparatus, partly in section and with the keyboard omitted;

Fig. 2 is a side elevation of Fig. 1, looking in the direction of the arrow X, but including the keyboard;

Fig. 3 is a section on the line C—C of Fig. 2;

Fig. 4 is a section on the line A—A of Fig. 1;

Fig. 5 is a similar section with certain parts omitted;

Fig. 6 is a view showing an alternative mechanism to that of Figs. 4 and 5;

Figs. 7, 8 and 9 show details;

Figs. 10, 11 and 12 show the mechanism for sending out a continuous series of impulses of long duration for synchronising purposes.

Referring now to the drawings, the apparatus shown therein is adapted to be driven by means of a manually rotatable handle, but it is to be understood that other driving means, such as an electric motor may be used. The handle 1 is fixed to a lever 2 clamped around a sleeve 3 fixed to a shaft 4. This shaft 4 drives, through the medium of a coiled spring, a shaft 9 which must be kept in continuous rotation whilst the trans-

mitter is operated. The shaft 9 drives the driving portions 12a and 16 of two toothed clutches, the driven portions of which are normally held stationary. When a key is depressed these clutches are tripped and sleeve 22 and shaft 30 are caused to rotate. Sleeve 22, which is driven at a much higher speed than shaft 30, actuates, by means of cams thereon, the transmitting contacts, whilst shaft 30 rotates until one of a helical series of levers 32 thereon releases the key 10 that has been depressed, whereupon sleeve 22 and shaft 30 are arrested.

The mechanism will now be described in detail. Upon the shaft 4, driven by means of handle 1, or by means of a motor, is fixed a cylindrical drum 7. The shaft 9 is supported in bearings to rotate freely and its axis is in line with the axis of shaft 4. One end of a coiled spring 8 is fastened to the interior of drum 7 and the other end to shaft 9, so that shaft 9 is driven from shaft 4 by tension applied to the spring 8. A gear wheel 10 fixed on shaft 9 meshes with gear wheels 11 and 12. Gear wheel 12 is fixed to the driving portion 12a of a toothed clutch. Gear wheel 11 is fastened on a stub shaft 13 to which is fastened a gear wheel 14 which meshes with gear wheel 15 fastened on the driving portion 16 of a second toothed clutch.

The keys 33 are arranged in three rows as in a teleprinter and are carried by key levers 34 30 all pivoted on a rod 35, and are held in position by individual springs 63. To each key lever 34 is fixed a pair of parallel plates 36 confining between them a two armed lever 39, 40, pivoted on the key lever by means of a knuckle joint 31 35 which permits limited movement only. The levers 39, 40 are held in position by springs 38 fixed thereto and to the key levers 34. When a key 33 is depressed the lower edge of one of the plates 36 displaces a lever 64, Fig. 3, pivoted at 40 its lower end. Each lever 64 carries a roller 65, and all the levers 64 are confined between fixed pins 66, the pin at one end only of the row being shown, in such manner that when one key lever 34 is depressed, the plate 36 turns the levers 64 45 on each side of it so that the rollers 65 are all in contact. Two keys cannot be depressed together because there is not sufficient room for displacement of the levers 64 to permit of this.

When a key lever 34 is depressed the depending arm 40 of the two arm lever attached thereto engages a frame 41 and tilts it anti-clockwise and with it the rod 42. Attached to rod 42 is a bent rod 68, and this in turning, draws by means of spring 59 a lever 69, pivoted at 70 and so 55

moves a frame 43 towards the ends of the key levers 34. The upper end of this frame 43 moves in above the end of the depressed key lever and below the ends of the other key levers 5 and so holds the keyboard locked.

Fixed to the rod 42 is a lever 45 (Figs. 4 and 5) pivoted to which is a latch 46, which engages with the end of a lever 48 under the action of a spring 47. Lever 48 is shaped as shown in Fig. 8, 10 is pivoted in blocks 49, 50 and carries a detent 51 that engages with the driven part 52 of a toothed clutch. The part 52 is urged towards the driving part 12a of the clutch by a spring 53 and is slidably mounted on a shaft carrying 15 a cam 54. Also fixed to the rod 42 is a lever 60 (Fig. 5) against the end of which rests a lever 61 tending to turn clockwise about its pivot 12 under the influence of a spring 73. When rod 42 is turned by the depression of a key, latch 46 20 pushes lever 48 against spring 71 to disengage detent 51 from the clutch part 52. The parts 51 and 52 of the clutch engage, and cam 54 is driven by the clutch. As the cam rotates the latch 46 is disengaged from the lever 48 thus 25 permitting lever 48 to arrest the part 52 after it has completed one revolution. At the same time the movement of lever 60 allows lever 61 to move clockwise in Fig. 5. Cam 54 after a period of rotation clockwise in Figs. 4 and 5 30 depresses a lever 55 and a turned over portion 62 of lever 61 can move over a nose 63 on lever 55 and hold it depressed. A lever 74 is provided normally held by a spring 75 against cam 54 to prevent any anti-clockwise rotation of such cam 35 and to provide a definite stop position therefor.

Lever 55 is, in the stationary position of cam 54, held against that cam by a spring (not shown) similar to spring 75. A second arm 56 of lever 55 carries a detent 57 which normally 40 holds the driven part 17 of a toothed clutch out of engagement with the driving part 16. On the depression of lever 55 by cam 54 this detent is raised and the clutch engages. A gear wheel 28 and cams 22, 23, and 76 are thereupon rotated. 45 Cams 22 and 23 act on levers 24 and 25 which carry contacts co-operating with fixed contacts 26, 27 to send reversals to line. Cam 76 co-operates with a lever 77 which holds the cam shaft in definite position when the clutch parts 50 16, and 17 are disengaged. The speed of the shaft carrying cams 22, 23 and 76 is controlled by a speed governor (not shown).

Gear wheel 29 meshes with gear wheel 21 on a stub shaft on which is fixed gear wheel 28. 55 The latter meshes with and thus drives a gear wheel 29 on a shaft 30. The latter carries a helical series of projections 32, one for each key lever and an indicating wheel 31. The shaft 30 is driven at such speed that it turns through 60 the distance between two adjacent characters on the wheel 31 for each reversal sent by the cams 22 and 23.

When the projection 32 corresponding to the depressed key lever engages the arm 39 of the lever pivoted thereto, the latter turns on its pivot and the depending arm 40 is disengaged from the frame 41. The latter is allowed to rise and the consequent turning of rod 42 re-engages latch 46 with the nose of lever 48. At 65 the same time lever 60 raises lever 61 so as to disengage the portion 62 thereof from the lever 55 and allow it to rise. The rise of lever 55 moves lever 56 to bring the detent 57 into re-engagement with the driven part 17 of the other clutch 70 75 and this part is withdrawn from engagement

with the driving part 16. The machine is thus brought to rest. The turning of rod 42 turns lever 68 and a bent rod 78 which engages therewith is moved to turn rod 70. The lever 43 is thus moved from engagement with the key levers 5 and the depressed key rises under the influence of its spring 63.

It will be observed that there is a definite delay period imposed by the mechanism between the depression of a key and the release for rotation of cams 22 and 23. This ensures, that, if one key is depressed immediately another is released, the two series of impulses do not run into one another, but there is a definite pause therebetween. This is accomplished by the arrangement that the depression of a key first releases a shaft carrying a cam 54 and this cam then releases the transmitting cam shaft.

An alternative mechanism for holding the lever 55 depressed after it has been once actuated by the cam 54 is shown in Fig. 6. In this case a lever 79 is fixed to rod 42, and pivoted to latch 80 is a lever 80 with a hooked end shaped as shown in Fig. 6. When rod 42 is turned clockwise in Fig. 6 on depression of a key the hooked end of lever 80 rides on a roller 81 mounted adjustably on a bell crank lever 82 pivoted at 83. When lever 55 is depressed by cam 54 latch 80 moves into the path of the end of lever 55. Thus when lever 55 is depressed by cam 54, it is held by latch 80. When the rod 42 is released so as to rotate in a counterclockwise direction the hooked end of latch 80 rises thus allowing lever 55 to rise simultaneously. At the same time the latch 80 engaging with the roller 81 is moved back out of the path of the end of lever 55. Thus the depression of a key does not immediately operate lever 55 but lever 55 is held operated until the key is released.

An indicator is provided to show the operator the tension applied to the spring 8 to warn him when it is too low, and to prevent the tension of spring 8 being increased beyond the limit. For this purpose a gear wheel 6 is provided on shaft 4 and a gear wheel 85 on shaft 7. Gear wheel 85 drives, through an idler gear 86, a gear wheel 87 fixed on a sleeve 88 freely turning on a shaft 91. Gear wheel 6 meshes with a gear wheel 89 on a sleeve 90 also freely 45 rotating on shaft 91. Carried on sleeves 90 and 88 respectively are gear wheels 92 and 93 which mesh with pinions 94 and 95 carried by a disc 96 secured to shaft 91. This forms a differential gear and rotates shaft 91 at the difference of the 50 speeds of gear wheels 6 and 85. Fixed to shaft 91 is a gear wheel 97 which, through gears 98, 99 and 100 drives a sleeve 101 freely rotatable on the shaft. Sleeve 101 carries a cam 102 which acts on levers 103 and 104 (Fig. 9). Lever 103 closes contacts 105 to light a warning lamp when cam 102 has rotated so far in one direction as to indicate that the tension of spring 8 is too 55 low. When cam 102 has rotated so far in the opposite direction that the tension of spring 8 is too great, lever 104 is moved by cam 102 into engagement with a cam 5 on the sleeve 3 and tends to hold the handle against being turned thus placing an extra load on the operator.

If a motor be used to drive the apparatus a friction clutch may be placed between the motor shaft and shaft 4 and the lever 104 acting on cam 5 will then hold shaft 4 stationary until the tension of spring 8 has fallen. Alternately the 70 75

cam can act to open the motor circuit when the spring is fully wound.

In order to ensure that the transmitter and any co-operating receiver are in corresponding positions a special synchronising key lever 106 (Fig. 10) is provided, the depression of which ensures the sending out of a continuous series of reversals during several rotations of the shaft 30 and the subsequent stoppage of the apparatus 5 in a definite position. The key lever 106 has pivoted thereto a lever 39a, 40a similar to the lever 39, 40 pivoted to other key levers, but there is no projection 32 on the shaft 30 corresponding thereto. The depending arm 40a is very 10 slightly longer than the depending arm 40 of the levers pivoted to other key levers. Key lever 106 carries a plate 107 which projects over an adjacent character key lever, say for letter T, and thus when the synchronising key is depressed 15 the adjacent key lever is also depressed. The frame 41, however, is tilted only by the arm 40a so that when a projection 32 engages the arm 39 of the lever on the key lever for letter T, it has no effect in releasing the key-board or in stopping the mechanism.

The shaft 30 carries a gear wheel 112 and mounted to be freely rotatable on a shaft parallel to shaft 30 is a gear wheel 110, which is formed with a gap 111 in its teeth. This gap is normally opposite wheel 112. Key lever 106 is extended beyond its pivot 35 and pivoted thereto is a horizontal latch 113 engaging with a bell crank lever 114 pivoted at 115. An arm of the bell crank lever 114 engages a detent 117 on wheel 110. Fixed to wheel 110 is an arm 109. When key lever 106 is depressed, latch 113 is removed from lever 114 which is pulled by spring 116 out of engagement with detent 117. Spring 118 one end of which is attached to arm 109 20 pulls this arm and so rotates wheel 110 until its teeth mesh with those of wheel 112. Wheel 110 is then rotated, arm 109 being carried round with it and spring 118 tensioned. This rotation continues until the gap 111 comes nearly 25 into the position shown in Fig. 12. As soon as the gear teeth come out of engagement spring 118 pulls arm 109 to rotate wheel 110 suddenly into the position shown in Fig. 12. In this last 30 part of the movement arm 109 gives a sudden blow to a bell crank lever 119 and turns it into contact with the arm 39a of the lever pivoted 35 to key lever 106 and so moves the depending arm 40a from engagement with the frame 41. The frame 41 rises until it engages with the depending 40 arm 40 of the lever pivoted to the key lever 5 for letter T. The control of the transmitter is now with the latter and when the shaft 30 reaches the position corresponding to letter T, the key lever for this letter is allowed to rise and the mechanism is restored to normal.

60 A step by step receiver which is adjusted into a definite position by the receipt of a series of impulses exceeding a given number, independently of the exact number of impulses is described in our co-pending application Ser. No. 182,200, filed Dec. 29, 1937, and the transmitter described 65 in the present application is intended to co-operate therewith.

What is claimed is:

1. A step-by-step telegraph transmitter, comprising a transmitting shaft, means for driving said shaft at a predetermined speed, transmitting contacts, means on said shaft to operate said contacts to transmit an even integral number of impulses not greater than four impulses per 70 revolution, a second shaft driven at a speed lower

than said transmitting shaft, a plurality of helically arranged projections on said second shaft, transmitter keys representing the characters to be transmitted, members respectively controlled by individual ones of said keys arranged to coact with a respective one of said projections to stop rotation of said shafts and determine the number of impulses transmitted and means controlled by depression of any key for releasing said shafts for rotation.

2. A transmitter according to claim 1 in which said second shaft is driven from said transmitting shaft through reduction gearing.

3. A transmitter for step-by-step telegraphy comprising a rotatable shaft, a plurality of transmitting keys, means actuated by depression of any of said keys for rotating said shaft into a position dependent upon the particular key depressed, a transmitting shaft geared to said first mentioned shaft, transmitting contacts controlled by said transmitting shaft, an intermediate shaft, and means operated after a predetermined period of rotation of said intermediate shaft for initiating operation of said transmitting shaft.

4. A transmitter according to claim 3, further comprising means for pivoting said keys on axes parallel to said first mentioned shaft, means mounted on pivoted levers for preventing simultaneous operation of two keys.

5. A transmitter according to claim 3, further comprising a plurality of levers for carrying said keys, and means for pivotally supporting said keys in a plurality of parallel rows.

6. A step-by-step telegraph transmitter comprising a transmitting shaft, means for driving said shaft at a predetermined speed, transmitting contacts, means on said shaft for operating said contacts upon rotation of said shaft, a second shaft geared to said transmitting shaft for operation at a lower speed, transmitting keys representing the various characters to be transmitted, means for releasing said transmitting and second shafts for a predetermined period of rotation, upon depression of any key, and means for delaying initiation of rotation of said transmitting shaft and said second shaft for a predetermined period.

7. A step-by-step transmitter comprising a rotatable shaft, a plurality of keys for representing the characters to be transmitted, means actuated by depression of a key for rotating said shaft to a position dependent upon the key depressed, means for transmitting a corresponding number of impulses during said rotation, and means for ensuring a predetermined delay between the depression of a key and the starting of said shaft.

8. A transmitter according to claim 7 in which said last named means comprising an intermediate shaft, means actuated by depression of a key for starting said intermediate shaft in rotation, and means actuated by said intermediate shaft after a predetermined period of rotation thereof for starting said first mentioned shaft into rotation.

9. A step-by-step transmitter as claimed in claim 7, further comprising a synchronizing key, means actuated by depression of said synchronizing key for transmitting a plurality of impulses greater than required for any character, and means for bringing the transmitter to rest in a position corresponding to a predetermined character.

ALFRED EDWARD THOMPSON.
